Kenneth D. Bixler, Huntington, N.Y., assignor to Diamond International Corporation, New York, N.Y., a corporation of Delaware

Filed Dec. 23, 1968, Ser. No. 15,095

Term of patent 14 years

Int. Cl. D7—02

U.S. Cl. D44—10

FIG. 1

FIG. 2

FIG. 3

FIG. 4

FIG. 1 is a perspective view of a pizza tray showing my new design;

FIG. 2 is a top plan view;

FIG. 3 is an enlarged edge elevational view; and

FIG. 4 is an enlarged sectional view on line 4—4 of FIG. 1.

The characteristic feature of the design resides in the particularly configured rim in combination with the stepped sidewall as shown.

I claim:

The ornamental design for a pizza tray, as shown and described.
